[57] CLAIM

The ornamental design for a colonic enema board, as shown.

DESCRIPTION

FIG. 1 is a perspective view of a colonic enema board, showing my new design;
FIG. 2 is a top plan view thereof;
FIG. 3 is a bottom plan view thereof;
FIG. 4 is a left side elevational view thereof, the right side elevational view being identical thereto;
FIG. 5 is a front end elevational view thereof; and,
FIG. 6 is a rear end elevational view thereof.

FIG. 4

FIG. 5

FIG. 6
